**LOCKABLE PLATE UNIT FOR USE ON A FURNI-
TURE LEG OR SIMILAR ARTICLE**

**Kenneth A. Green, R.R. 2, Cambridge, Ohio 43725, and
Lawrence A. Streblow, 2317 Springbrook Road, Kenosha,
Wis. 53140**

Filed Nov. 23, 1970, Ser. No. 26,134

Term of patent 14 years

Int. Cl. D6—06

U.S. Cl. D6—191

FIG. 1

FIG. 1 is a perspective view of the assembled lockable plate unit for use on a furniture leg or similar article showing our new design,

FIG. 2 is an exploded elevational view of the complementary locking plates shown in FIG. 1,

FIG. 3 is a view similar to FIG. 2 showing a second embodiment thereof,

FIG. 4 is a side view of the assembled plates shown in FIG. 1,

FIG. 5 is a side view showing the plates in FIG. 3 assembled,

FIG. 6 is an exploded perspective view of the respective complementary plates shown in FIG. 1,

FIG. 7 is a view similar to FIG. 2 showing another embodiment thereof,

FIG. 8 is a view similar to FIG. 3 showing another embodiment thereof,

FIG. 9 is a side view showing the respective complementary plates in FIG. 7 assembled,

FIG. 10 is a side view showing the respective complementary plates in FIG. 8 assembled, and

FIG. 11 is an exploded perspective view of the respective complementary plates shown in FIG. 7.

We claim:

The ornamental design for a lockable plate unit for use on a furniture leg or similar article, as shown and described.
